Primary Examiner — Mary Ann Calabrese*Assistant Examiner* — Jennifer L Rempfer(74) *Attorney, Agent, or Firm* — McAndrews, Held & Malloy, Ltd.(57) **CLAIM**

The ornamental design for a lower body garment gusset panel with butterfly shape, substantially as shown and described.

DESCRIPTION

FIG. 1 is a top rear perspective view of a lower body garment gusset panel with butterfly shape of the present invention, as it may be used in an undergarment. The broken lines of the undergarment show the claim in context and are not claimed; FIG. 2 is an enlarged plan view of the claimed lower body garment gusset panel with butterfly shape design; FIG. 3 is an enlarged front elevation view of the claimed lower body garment gusset panel with butterfly shape design; FIG. 4 is an enlarged rear elevation view of the claimed lower body garment gusset panel with butterfly shape design; and, FIG. 5 is an enlarged right side elevation view of the claimed lower body garment gusset panel with butterfly shape design (the left side elevation view is a mirror image thereof). The broken lines shown on the lower body gusset panel with butterfly shape represent unclaimed features.
